his Attorneys

UNITED STATES PATENT OFFICE.

WILLIAM L. WALKER, OF NEW YORK, N. Y., ASSIGNOR TO WALKER SIGNAL AND EQUIPMENT CORPORATION, OF NEW YORK, N. Y., A CORPORATION OF DELAWARE.

SOUND-DETECTING APPARATUS.

Application filed January 4, 1918. Serial No. 210,380.

To all whom it may concern:

Be it known that I, WILLIAM L. WALKER, a citizen of the United States, and resident of New York, in the county of New York and State of New York, have invented new and useful Improvements in Sound-Detecting Apparatus, of which the following is a specification.

This invention relates to sound detection and more particularly to the detection of sounds in water and to submarine signaling. While the present invention is adapted to a variety of uses it is particularly applicable in conjunction with the inventions disclosed in my prior applications Sr. No. 161,179, filed April 11, 1917; Sr. No. 176,299, filed June 22, 1917; and Sr. No. 202,680, filed November 19, 1917. The aforesaid applications relate to improved apparatus for detecting sounds, especially under water, while the present invention is more particularly concerned with the conversion of the sound energy into electrical energy, or the control of electrical energy with the sound energy, and the treatment of the electrical energy.

In detecting signals or sound disturbances under water it is sometimes necessary to deal with signals or disturbances of extremely small intensity and at other times to receive signals or disturbances of comparatively large magnitude. The detection of sound waves of minute intensity requires sensitive mechanism while the heavy disturbances necessitate means which will handle relatively large amounts of energy without damage. A universal system must possess delicacy to detect faint sounds and yet must have a sufficiently wide range of adaptability to receive heavy impulses. Moreover, the system should be adapted to discriminate or distinguish between sounds of various characters and be adjustable to detect any one sound from a miscellany of sounds.

The principal object of the present invention is to attain the aforesaid results more perfectly than has heretofore been possible, viz, to attain great sensitivity, to be able to receive heavy signals, to distinguish between sounds of different characters, and to afford adjustment to receive a sound of a particular character.

In general the invention consists in receiving the sound emanating to the receiv-

ing station, converting the sound into electrical current variations, and then differentiating the component of current variation corresponding to the sound or signal to be detected. Thus when a miscellany of sounds reach the receiving station as a composite sound, the composite sound is first converted into a variable electrical current of composite character and from this composite current the component corresponding to the signal or sound to be detected is selected and transmitted to an indicating or recording instrument. The selection of the particular current component is preferably attained by the conjoint use of a unique vibrator hereinafter described and a microphonic cell arranged as disclosed in my said application Sr. No. 202,680, although it is to be understood that in certain aspects of the invention either the vibrator or the microphonic cell may be widely varied. Moreover, the sound-responsive mechanism of the system may and preferably does assist in selecting the sound to be detected.

In the accompanying drawings,—

Figure 1 is a diagrammatic view of one embodiment of the invention;

Figure 2 is an end elevation of a cylindrical switch forming one element of Fig. 1;

Figure 3 is a development of the cylindrical switch;

Figures 4, 5, 6 and 7 show various circuit connections available with the cylindrical switch;

Figure 8 is a side elevation of the preferred embodiment of my improved vibrator;

Figure 9 is a plan view of the vibrator;

Figure 10 is a transverse section on line 10—10 of Fig. 8;

Figure 11 is a transverse section on line 11—11 of Fig. 8;

Figure 12 is a transverse section on line 12—12 of Fig. 8;

Figure 13 is a side elevation of a modified vibrator;

Figure 14 is an elevation of one form of vibrator adjusting means;

Figure 15 is a transverse section on line 15—15 of Fig. 14; and

Figure 16 is an elevation of a modified form of adjusting means.

The embodiment of my improved system shown in Fig. 1 comprises sound-responsive

mechanism A adapted to receive sound impulses and convert them into electrical impulses, an amplifier B for amplifying the electrical impulses, an electromagnet device 5 C for selecting from the electrical impulses the component corresponding to the sound to be detected, and a receiver D for reproducing the component of sound.

The sound-responsive mechanism A is 10 preferably of the type disclosed in my prior application Sr. No. 202,680, which consists of a plurality of microphonic cells 1 and 2 mounted on an oscillating arm 3 which is arranged to be oscillated by means of a diaphragm 4 the outer face of which is exposed 15 to the water or other medium through which the sounds are received and the inner face of which carries a rubber ring 4' to render the diaphragm aperiodic. Each microphonic cell is mounted on the lever arm through the medium of one of its electrodes and the other of its electrodes is free to move with the first electrode except as retarded by its inertia and by damping means which may comprise a 20 disk 5. Thus the two electrodes of each microphone move together when the lever arm is moved relatively slowly whereas when the lever arm is rapidly oscillated the retarded electrode is unable to follow the movement and relative motion takes place between 25 the two electrodes resulting in variations of current in the microphone circuits 6 and 7. These current variations are transmitted through the switch S to the audion B and 30 give rise to current variations of increased magnitude in the circuit of electromagnet C, the batteries 8 and 9 supplying potential to the input and output circuits of the audion respectively and the battery 10 serving to 35 heat the filament of the audion to incandescence.

The switch S is interposed in the circuit to effect various connections of the microphones with the audion B or electromagnet 45 device C. The switch is rotary and has four sets of contacts 11-11', 12-12', 13-13' and 14-14', the contacts 11, 12, 13 and 14 being adapted to contact with the contacts 15, 16, 17 and 18 of the microphone circuits and 50 the contacts 11', 12', 13' and 14' being adapted to contact with the contacts 19 and 20 of the audion input circuit. When the contacts 11 and 11' engage the respective sets of contacts 15-18 and 19-20 as shown in Figs. 1 55 and 2, the microphones 1 and 2 are connected in series with the audion as shown in Fig. 4; when the contacts 12 and 12' engage the sets of contacts 15-18 and 19-20 the microphones are connected in parallel to the audion; and when in each of the other positions 60 one of the microphones is singly connected to the audion. By this arrangement the microphones may be connected in series, parallel or individually to the audion depending upon 65 the intensity of the sounds received. More-

over, if the sounds be of sufficient intensity the audion may be cut out of the circuit in any suitable manner as by closing switch 21.

The selecting and reproducing apparatus 70 generally shown at C in Fig. 1 and specifically illustrated in Figs. 8 to 12, comprises a vibratory band or strip 22 mounted at spaced intervals between knife-edge supports 23 so as to vibrate to and fro. The knife-edge supports are mounted on a calibrated circular bar 24 so as to be adjusted therewith as is shown particularly in Fig. 11, the frame 25 of each knife-edge support surrounding the bar 24 and being provided with a threaded projection 26 extending upwardly into a groove 36 in the lower side of the bar containing a threaded rod 27 journaled in the ends of the bar. The opposite ends of the rod 27 are threaded in opposite directions so that rotation of the rod in one direction moves the supports toward each other and in the other direction away from each other, handles 28 fitting over the opposite ends of the bar 27 with which to rotate the bar. The rod 24 is supported at its opposite ends by bases 29 and at its middle by a base 30. A bearing 31 is mounted on the base 30 in the groove 36 by means of screws 32 to support the central portion of the rod 27.

The threaded projections 26 are mounted on the frames 25 by means of screws 33 so as to project upwardly into grooves 36 around rod 27. The knife-edge supports 23 are disposed in recesses in frame 25 so as to be reciprocated inwardly or outwardly by screws 34 to permit the insertion or removal of a band of any desired width. Plates 35 are fastened over the said recesses by means of screws 37.

The electromagnetic means 38 disposed in the output circuit of the audion in Fig. 1 is mounted on the central frame 30 by means of a bracket 39 which is adjustable inwardly and outwardly by means of a screw 40 threaded through a lug 41 fastened to the side of frame 30 by a screw 42, the screw 42 cooperating with a slot in base 30 to hold the bracket in adjusted position.

On the side of the vibratory band opposite to the electromagnet is mounted a microphonic cell 44. The cell is mounted on the vibratory member through the medium of its diaphragm 45 and an air-resisting disk 46 is mounted on the rear 115 of the cell to retard or damp the movement of the body portion of the cell. As the vibratory member vibrates to and fro the diaphragm vibrates with it. If the movement of the vibratory member and diaphragm is relatively slow the body portion of the cell and the disk follow the movement so that no relative movement takes place between the two electrodes of the cell and therefore no current variation is pro- 120 125 130

duced in the microphone circuit. However, when the vibrator vibrates relatively rapidly the body of the microphone cannot follow the movement of the diaphragm, especially when employing damping means such as illustrated by the disk 46, and the diaphragm is flexed back and forth giving rise to a variable current of the frequency of vibration of the vibrator. Instead of the disk 46 any suitable damping means may be employed as more fully set forth in my said application Sr. No. 202,680.

The vibrator may be made to respond predominantly to any desired frequency of impulses by adjusting the supports 23 toward or from each other. For example, if it is desired to select a signal of known frequency from a miscellany of sounds the vibrator is adjusted to the known frequency and will respond predominantly to the component of the compound current wave in the audion circuit which represents the signal. This may be briefly explained as follows:

The miscellany of sounds striking the sound-responsive diaphragm 4, including the signal to be detected, is reproduced in the input circuit of the audion as a composite current wave corresponding to the composite sound wave more or less closely depending upon the character of the sound-receiving apparatus A. This composite current wave is reproduced and amplified by the audion with substantially no change except in magnitude. The composite amplified wave thus transmitted to the vibrator is differentiated by the vibrator, when the vibratory member is adjusted to the frequency of the component signal, so that the signal is alone transmitted to the receiver D. When the signal ceases the vibrator ceases to vibrate to any appreciable extent.

Supplementary or alternative methods of adjusting the vibrator are shown in Figs. 13 to 16. Fig. 13 shows weights 47 adjustably mounted on a vibratory member 48. These weights are U-shaped as shown in Fig. 14 and their inner edges are relatively narrow as shown in Fig. 15 so that when clamped to the vibrator by the thumb-screws 49 they engage a relatively narrow area of the vibrator. In order to supplement the inertia of the weights the air resistance of disks 50 mounted on the weight may be utilized as illustrated in Fig. 16.

In supplementing the device shown in Fig. 9, for example, with weights such as shown in Figs. 13 to 16, the vibration of the band 32 may be varied by shifting the weights toward or from the center of the band, the weights preferably being maintained equidistant from the magnet 28 at the center.

I claim:

1. An apparatus for detecting sounds of a

particular character comprising a plurality of sound responsive devices adapted to transform sound into electrical impulses, a sound selecting device adapted to transform electrical impulses into mechanical impulses, means for transforming said mechanical impulses into electrical impulses having different characteristics from those impressed on the sound selective device, said transforming means including vibratory means, movable knife-edge supports therefor to adjust the period of vibration thereof whereby desired frequencies are augmented and undesired frequencies damped; conductors connecting the sound responsive devices to the sound selecting device and amplifying means associated with said conductors whereby additional energy is given the electrical means for operating the vibratory member of the sound selecting device.

2. In apparatus of the character described, the combination of an elongate vibratory member, sound-responsive means for vibrating said member, movable supports engaging the elongate member at spaced intervals whereby said member may be tuned to a certain frequency so as to constitute a barrier to trains of impulses of other frequencies, and means for conjointly moving the supports to and from each other.

3. In apparatus of the character described, the combination of an elongate vibratory member, electromagnetic means for vibrating said member, current-varying means arranged to be actuated by said member, movable supports engaging the elongate member at spaced intervals whereby said member may be tuned to a certain frequency so as to constitute a barrier to trains of impulses of other frequencies, and means for conjointly moving the supports to and from each other.

4. In apparatus of the character described, the combination of a flexible band knife-edge means for supporting the band at spaced intervals so that the portion of the band therebetween may vibrate to and fro, means for conjointly moving the knife-edge means to and from each other, and current-varying means arranged to be vibrated by said band, the band being tuned to vibrate predominantly at a relatively high frequency.

5. In apparatus of the character described, the combination of a flexible band, supports engaging the band at spaced intervals so that the portion of the band therebetween may vibrate to and fro, and means for conjointly moving the supports to and from each other.

6. In apparatus of the character described, the combination of a flexible band, supports engaging the band at spaced intervals so that the portion of the band therebetween may vibrate to and fro, means for conjointly moving the supports to and from each other, means for vibrating the band, and means

1
associated with the band intermediate the supports for affecting the frequency of vibration of the band.

7. In apparatus of the character described, 5 the combination of a flexible band, supports engaging the band at spaced intervals so that the portion of the band therebetween may vibrate to and fro, means for conjointly moving the supports to and from each other, and means adjustably mounted on the band 10 intermediate the supports for regulating the vibration of the band.

8. In apparatus of the character described, 15 the combination of a flexible band, supports engaging the band at spaced intervals so that the portion of the band therebetween may vibrate to and fro, means for conjointly moving the supports to and from each other, and air-resistors adjustably mounted on the band 20 intermediate the supports for regulating the vibration of the band.

9. In apparatus of the character described, 25 the combination of a flexible band, supports engaging the band at spaced intervals so that the portion of the band therebetween may vibrate to and fro, means supported at a midpoint between said supports for vibrating the band, and means for conjointly moving the supports to and from each other and

maintaining said means in the same position 30 relative to the supports.

10. In apparatus of the character described, 35 the combination of a base member, supports adjustable thereon, a flexible band engaged in said supports, means mounted on the base at a midpoint between said supports for vibrating the band, and an adjusting rod having means engaging said supports whereby a movement of the rod in one direction moves said supports toward each other and a movement of the rod in the other direction moves said supports away from each other.

11. In apparatus of the character described, 45 the combination of a flexible band, supports engaging the band at spaced intervals so that the portion of the band therebetween may vibrate to and fro, electrical means for vibrating the band, means for adjusting the correct distance between the vibrating means and the vibrating band and means associated with the band intermediate the supports for affecting the frequency of vibration of the band.

Signed by me at Boston, Mass., this 10th 55 day of December, 1917.

WILLIAM L. WALKER.
